UNITED STATES PATENT OFFICE

158,280

HOLDER FOR MANICURING ABRASIVE
STRIP

Herbert S. Heineman, Hollywood, Calif.

Application October 18, 1948, Serial No. 149,160

Term of patent 14 years

(Cl. D86—10)

To all whom it may concern:

Be it known that I, Herbert S. Heineman, a citizen of the United States, residing in Hollywood, in the county of Los Angeles and State of California, have invented a new, original, and ornamental Design for a Holder for Manicuring Abrasive Strip, of which the following is a specification, reference being had to the accompanying drawing, forming a part thereof.

Fig. 1 is a side elevational view of a holder for manicuring abrasive strip showing my new design.

Fig. 2 is an edge view of the article illustrated in Fig. 1.

Fig. 3 is a view similar to Fig. 1, but illustrating the outer face of the device.

Fig. 4 is a cross-section taken on the line 4—4 of Fig. 3.

Fig. 5 is a cross-section taken on the line 5—5 of Fig. 3.

I claim:

The ornamental design for a holder for manicuring abrasive strip, as shown.

HERBERT S. HEINEMAN.
